PAPER MACHINE

Albert Richards, Gladstone, Oreg.

Application September 28, 1937, Serial No. 166,184

1 Claim. (Cl. 34—48)

This invention appertains to new and useful improvements in paper machines and more particularly to an auxiliary rope carrier for paper machine driers. In paper machines a carrier is employed to carry a narrow strip of paper over the paper machine driers. Oftentimes in carrying the strip paper over the driers, the paper will break on the driers or drop out of the ropes and wrap around the driers forming a wad of wet paper. When this wet wad of paper forms under the ropes running on the conventionally formed driers, the ropes are generally displaced from the grooves of the driers and result in breaking of the ropes or tangling of the same. This causes a shut down of the driers and the inactivity of an entire paper machine before the ropes can be replaced.

The principal object of the present invention is to provide an auxiliary rope grooveway for each of the driers so that in the event the ropes become displaced they will be caught by the auxiliary grooveways.

Other important objects and advantages of the invention will become apparent to the reader of the following specification.

In the drawings:—

Figure 1 represents a diagrammatic view showing the rope arrangement of a conventional paper machine.

Figure 2 is an end elevational view of one of the driers.

Figure 3 is an enlarged fragmentary detailed sectional view on the line 3—3 of Figure 2.

Figure 4 is a fragmentary inside elevational view of the auxiliary structure.

Referring to the drawings wherein like numerals designate like parts, it can be seen in Figure 1, that numerals 5—6 represent the lower and upper driers over which the pair of ropes travel.

The outside rope is denoted by numeral 7 while the inside rope is denoted by numeral 8. Numeral 9 generally refers to a press in which numeral 10 is the guide roll. Numeral 11 represents the receiving roll. In the conventional paper machine the ropes 7—8 are carried in grooves on the front ends of the driers. These ropes travel close

together except where they are made to approach each other as at the press 9 so as to grip the end of the tail of paper placed between them.

Assuming in Figure 3 that numeral 5 represents one of the lower driers, it can be seen that the drier has the front end wall 12 and the extending peripheral portion 21 beyond this end wall. The cylindrical portion of the drier is provided with the internal end flange 14. It can be seen that the conventional drier has the grooveway 15 therein in which the ropes 7—8 are trained.

The structure forming the present invention is generally referred to by numeral 16 and consists of an annulus 17 divided into a multiplicity of sections α . Each of these sections α has a lug 18 extending inwardly therefrom and apertured to receive an elongated machine screw 19 which also extends through the end wall 12 and threads into the aforementioned flange 14.

The annulus 17 is provided with the circumferentially extending outstanding flange 20 which extends outwardly somewhat of the flange 21 of the conventional drier structure, so that in the event the ropes 7—8 step out of the grooveway 15 they are caught by the annulus 17.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

An attachment for the drums of paper making machines of the type having rope grooves, said attachment consisting of an arcuate plate adapted to be secured to the rope groove end of a drum and having at its outer edge, an outwardly extending flange in spaced relation to the adjacent end of the drum and projecting in a direction radially with respect to the drum beyond the periphery of the drum to catch a rope displaced from the rope groove of the drum.

ALBERT RICHARDS.
